CLAIM

U.S. PATENT DOCUMENTS

The ornamental design for a computer display panel with graphical user interface, as shown and described.

DESCRIPTION

D671,954 S * 12/2012 Wojcik D14/486
 9,092,556 B2 * 7/2015 Amble A61B 5/7475
 9,615,809 B2 * 4/2017 Lee G06T 7/0002
 10,169,535 B2 * 1/2019 Mentis A61B 1/0005
 10,417,326 B2 * 9/2019 Shimomura G06F 3/0481
 D885,425 S * 5/2020 Lu D14/486
 11,024,420 B2 * 6/2021 Shimomura G16H 30/40
 D926,207 S * 7/2021 Zheng D14/486
 D926,208 S * 7/2021 Zheng D14/486

The FIGURE is a front view of a computer display panel with graphical user interface, showing our new design. The broken lines in the drawing represent portions of the computer display panel and the graphical user interface that form no part of the claimed design.
